Application May 26, 1934, Serial No. 727,649

7 Claims. (Cl. 181—48)

This invention relates to improvements in mufflers or silencers for use in connection with silencing the noises of the exhaust of internal combustion engines.

5 The objects of this invention are to provide a through type or low pressure muffler of simple design which attenuates the power impulses or resonant sound waves; also to provide within a muffler resonator chambers having fundamental frequencies corresponding to the fundamental resonance frequency and related harmonics of the tail pipe leading from the muffler to the air; also to provide a muffler which includes outer resonating chambers which are connected by 10 means of constricted passages or necks to inner chambers communicating through a series of small openings or perforations with a conduit or passage for exhaust gases; also to provide a muffler of this type in which the resonator chamber and neck is so proportioned as to eliminate 15 sounds caused by the resonance of the tail pipe leading from the discharge end of the muffler to the air; also to provide a muffler in which the ends of the intermediate shell form necks with an imperforate portion of the main gas conduit 20 through the muffler communicating with a resonance chamber; also to provide a muffler of this kind in which an end portion of the intermediate shell is supported on the main conduit by longitudinal spacing members which also form a plurality of separate neck portions communicating with a resonator chamber; also to provide a muffler of this type in which a perforated baffle is interposed between the resonance chamber and the neck portion of the muffler; also to 25 improve the construction of mufflers of this kind in other respects hereinafter specified.

In the accompanying drawings:

Fig. 1 is a side view of a muffler embodying 30 this invention and connected with an exhaust and a tail pipe.

Fig. 2 is a longitudinal central sectional elevation of the muffler.

Fig. 3 is a transverse sectional view thereof, 35 on line 3—3, Fig. 2.

Figs. 4 and 5 are longitudinal central sectional views of mufflers of modified construction.

Fig. 6 is a transverse section of the muffler shown in Fig. 5 on lines 6—6, Fig. 5.

Fig. 7 is a longitudinal central sectional view 40 of a muffler of another modified form.

Figs. 8 and 9 are transverse sections thereof on lines 8—8 and 9—9, Fig. 7.

Referring to Fig. 1, A represents the muffler 45 to which an exhaust pipe B leading from the

engine is connected and C represents the usual tail pipe leading from the discharge end of the muffler to the rear of the vehicle on which the muffler is used.

I have found that in the design of mufflers of the type having sound absorbing or resonating chambers, the length of the tail pipe C has an important bearing upon the silencing action of the muffler. It has been found, for example that a muffler which effectively silences the noise of the exhaust of a certain type of engine when used in connection with a tail pipe of a certain length, will be noisy when used with a tail pipe of different length. I have found that while a long tail pipe is effective in reducing a certain noise called "blatt", such tail pipe, nevertheless, resonates at both odd and even harmonics and has two distinct fundamental frequencies as a result of being only partially closed at the muffler end.

For example, a well known eight cylinder automobile has resonance periods at 10 $\frac{1}{4}$, 16, 21 $\frac{1}{2}$, 26 $\frac{3}{4}$ and 32 miles per hour. The engine of this automobile makes 3231 revolutions per mile and the tail pipe leading from the muffler is six feet long. This gives engine impulse frequencies of 38, 57, 76, 95 and 114 per second respectively at these various speeds. The tail pipe fundamental resonance frequencies are

$$\frac{1368}{2 \times 6} = 114 \text{ and } \frac{1368}{4 \times 6} = 57$$

per second corresponding to resonance periods at 32 and 16 miles per hour, the velocity of sound in hot exhaust gases being approximately 1368 feet per second. The other resonance periods were not as loud as those at 16 and 32 miles per hour, but it will be noted that they have harmonic relation so that any attenuation of the 16 or 32 miles per hour periods will likewise attenuate the other periods, as well as their higher harmonics.

From the foregoing, it will be realized that any change in the tail pipe length changes its resonance. Filters designed to attenuate very broad bands of sound to accommodate any length of tail pipe are not efficient from a silencing standpoint unless they comprise a plurality of units, or are of a size beyond that practical for average installations.

In mufflers embodying this invention, I have limited the main filters to two, of which at least one is similar to the Helmholtz neck type resonator. Such resonators can be made with resonance bands broad enough to eliminate the sound due

to the resonance of the tail pipe and are very efficient otherwise. In some cases, one resonator is tuned to the frequency

$$5 \quad N = \frac{c}{4L}$$

and the other to

$$N = \frac{c}{2L}$$

10 in which "N" is fundamental frequency to be attenuated, "c" the velocity of sound in the medium and "L" the length of the tail pipe. In other cases, I may tune these resonating chambers to

$$15 \quad N = \frac{c}{2L}$$

and

$$N_2 = \frac{c}{L}$$

20 in which "N₂" is the half harmonic of "N". I do not limit my invention to any particular combination of resonators, except that they must either have resonance frequencies the same as the fundamental frequencies or harmonic frequencies of 25 the tail pipe.

I have found that by substituting the proper values in the following equations, approximate values may be obtained for the unknown quantities. Corrections should be then undertaken, 30 always bearing in mind that any increase in the dimensions of the cavity, any increase in the length of the neck of the resonator, or any decrease in the area of the neck will lower the resonator's fundamental frequency. The formula 35 which I have devised is as follows:

$$N = \phi \frac{c}{2\pi} \sqrt{\frac{s}{Iv}} = \phi \frac{cR}{2\pi R_1} \sqrt{\frac{I}{LL_1}}$$

in which

40 ϕ =area of perforation in conduit communicating with the neck, divided by the cross-sectional area of the conduit

c =velocity of sound in the medium

45 s =area of resonator neck

l =length of resonator neck

v =volume of resonator cavity

R =radius of resonator neck

R_1 =radius of resonator cavity

50 L =length of resonator cavity

N =frequency to be attenuated.

The area of those slots or perforations in the conduit which communicate with the neck should not exceed the cross-sectional area of the conduit and the cross-sectional area of the resonator neck should be about equal to the cross-sectional area of the conduit.

In order to construct a muffler incorporating the principles outlined, and to which the foregoing formulae are applicable, a number of mufflers are illustrated in the drawings merely by way of examples, it being understood that my invention may be embodied in mufflers of other constructions than those shown. In all of these 60 mufflers a central straight through passage or conduit is employed which has a relatively large number of perforations therein, an intermediate shell surrounding the inner conduit and connected therewith by means of one or more baffles, 65 thus forming sound impedance chambers. The intermediate shell is surrounded by an outer shell forming with the intermediate shell one or more resonator chambers or cavities, each of which connects with an impedance chamber preferably 70 around the adjacent end of the intermediate 75

shell, and I furthermore provide a neck connecting the impedance chamber with the resonator chamber, the neck being formed between an imperforate portion of the inner conduit and the intermediate shell. The muffler shown on Figs. 5 2 and 3 includes the usual outer shell 10, the ends of which are secured to end headers or baffles 11 and 12 which have openings or tubular extensions to which the exhaust pipe B and the tail pipe C are respectively connected, for example, 10 by means of clamps 14 and 15. 16 represents an inner shell or conduit which is provided throughout the greater portion of the length thereof with a plurality of perforations or openings 17. In the particular construction shown, the inner conduit 15 is also provided with integral outwardly bent portions adjacent to the perforations forming louvers for discharging gases from the inner shell in a tangential direction, but openings of any other kind may be provided in the inner conduit or 20 shell.

18 represents an intermediate shell spaced between the inner conduit and the outer shell and 19 represents a baffle or partition arranged between the intermediate and outer shells to divide 25 the space between these shells into two separate chambers. This partition may be omitted or a plurality of partitions may be employed, if desired. Other partitions 20, 21, and 22 are arranged between the inner conduit and the intermediate shell to form a plurality of sound impedance chambers 24, 25, 26 and 27.

It will be noted that the portion of the inner shell or main conduit adjacent to the ends thereof is unperforated, thus forming between the 35 inner and intermediate shells an annular neck portion 33 through which sound or impulse waves may pass from the impedance chamber 24 to a resonating chamber 28 between the intermediate 40 and outer shells. From the impedance chamber 27 sound or impulse waves may pass through a neck 34 to another resonator chamber 29. The rear end of the intermediate shell is shown unsupported and is provided with a reinforcing cuff 36 formed by bending the metal of the end of the 45 intermediate shell back against itself. The front end of the intermediate shell is supported from the outer shell by a partition or perforated baffle 31 having a series of apertures 32 therein to permit sound from the neck portion 33 to pass 50 through the apertures 32 into the resonating chamber 28.

In view of the fact that the cross sectional areas of the neck portions 33 and 34 are materially less than those of the chambers 28 and 29, this relation of the neck portions to the chambers results in resonating chambers operating on the principle of the Helmholtz resonator. The perforated partition or baffle 31 has been found desirable in that it eliminates certain metallic 60 sounds from the noise of the exhaust. If desired, a similar partition could be used at the other end of the muffler, or in certain cases, it may be possible to omit the partition 31 or to replace the same by other means for eliminating 65 certain metallic-like sounds from the exhaust.

It will be obvious that the formula can be easily applied to the proportioning of the parts of the muffler to eliminate certain objectionable sounds and from the formula, it will be obvious that by 70 lengthening the neck, which, for example, could be done by providing a longer portion of the inner conduit without perforations, the frequency of the resonating chamber will be lower. Also the larger the cavity of the resonating cham- 75

ber the lower its frequency. The sizes of the resonator cavities or chambers 28 and 29 can, of course, be readily varied by adjusting the baffle 19 or by variations in the diameters of the intermediate or outer shells. In applying the formula to any of the mufflers shown in the drawings, the length of the tail pipe must include the length of the adjacent imperforated portion of the inner shell or conduit.

- 10 The muffler shown in Fig. 4 is somewhat similar in construction to that shown in Figs. 2 and 3. In this muffler, the main conduit or inner shell 35 is provided with circular perforations, and the intermediate shell 36 has its ends unsupported. 15 In this muffler, two baffles 37 are provided between the inner and intermediate shells, thus forming three sound impedance chambers 38, 39 and 40, the chamber 38 communicating through a neck portion 41 with a resonance chamber or cavity 42 and the sound impedance chamber 40 communicates through a neck 43 with a resonator chamber or cavity 44.

The muffler shown in Figs. 5 and 6 is somewhat similar to those already described, except that in this case the intermediate shell is provided with an outwardly flared end 48 and the opposite end of the intermediate shell is supported on a baffle or supporting member 49 secured to an end head or baffle 50 and provided with perforations 51, this baffle being similar in its action to the baffle 31 described in connection with Figs. 2 and 3.

In the muffler shown in Figs. 5 and 6, a neck portion 52 is provided at one end of the intermediate shell, while at the other end the perforations extend almost to the end of the intermediate shell so that practically no neck is formed between the inner and intermediate shells, but a short neck portion is formed between the outwardly flaring end 48 of the intermediate shell and the end head or baffle 54 of the muffler. It will be obvious that by variation of the length of the neck and the size of the resonating chambers between the intermediate and outer shells, the muffler can be readily tuned in accordance with my formula to eliminate certain wave bands which would produce resonance in the tail pipe.

In Figs. 7 to 9 is shown another slightly modified form of muffler in which only a single baffle or partition 60 is provided between the inner or main conduit 61 and the intermediate shell 62. In this construction, the neck connecting with the impedance chamber 63 is in the form of a plurality of separate ducts or passages. It will be noted that by reference to Figs. 7 and 9, the intermediate shell has a plurality of longitudinally inwardly extending ribs or grooves 65 formed therein, the inner surfaces of which contact with the inner shell or conduit 61, thus forming a member of elongated separated ducts or necks 66 leading from the sound impedance chamber 63 to the resonator chamber 67. These grooves or depressions 65 in the intermediate shell, in addition to forming a plurality of separated passages also serve to support the outer end of the intermediate shell from the inner shell or conduit. It is not intended, however, to limit this invention to the formation of these depressions or grooves on the intermediate shell, since any other spacing means connecting the conduit and intermediate shell may be employed to divide the neck portion of the resonator chamber into a plurality of neck portions for eliminating from the exhaust certain high frequency metallic-like sounds generated in the muffler.

75 At the discharge end of the muffler, the outer

end of the intermediate shell is provided with a pair of inwardly pressed portions 68 which are also arranged to contact with the inner shell, to support this end of the shell from the inner conduit. Between these inwardly pressed portions 68 are formed passages 69 connecting the neck 70 with the resonance chamber 71. Any other means for supporting the ends of the intermediate shell on parts of the muffler may be employed, and other means for forming elongated channels or tubes 10 of reduced cross sectional area between the inner and intermediate shells may be employed, if desired. By means of the construction shown in Figs. 7 to 9, the cross sectional area and length of the resonator neck can readily be varied so as to 15 produce a combination of neck and resonance chamber by means of which a definite frequency band of sound can be attenuated.

I claim as my invention:

1. A muffler comprising an imperforate outer shell, apertured end heads connected to said outer shell, a conduit connecting with the apertures in said heads to provide a through passage for exhaust gases, said conduit having a portion of its length provided with a plurality of relatively small apertures, an intermediate shell continuous from end to end thereof and having both ends spaced from said heads, a partition between said conduit and said intermediate shell and dividing the space between said conduit and intermediate shell into 30 a plurality of inner elongated chambers a partition dividing the space between said intermediate and outer shell into a plurality of outer resonator chambers, the inner chamber at each end of the muffler communicating around the adjacent end 35 of the intermediate shell with a resonating chamber, said conduit being provided with apertures opening into each inner chamber and being provided with an imperforate portion near an end of said conduit forming with the intermediate 40 shell a resonator neck connecting with a resonator cavity.

2. A muffler comprising an imperforate outer shell, apertured end heads connected to said outer shell, a conduit connecting with the apertures in 45 said heads to provide a through passage for exhaust gases, said conduit having a portion of its length provided with a plurality of relatively small apertures, an intermediate shell continuous from end to end thereof and having both ends 50 spaced from said heads, a partition between said conduit and said intermediate shell and dividing the space between said conduit and intermediate shell into a plurality of inner elongated chambers, a partition dividing the space between said 55 intermediate and outer shell into a plurality of outer resonator chambers, the inner chamber at each end of the muffler communicating around the adjacent end of the intermediate shell with a resonating chamber, said conduit being provided with apertures opening into each inner 60 chamber, and a tail pipe which has fundamental resonance frequencies in harmonic relation to those of the resonator chambers within said muffler.

3. A muffler comprising an imperforate outer shell, apertured end heads connected to said outer shell, a conduit connecting with the apertures in said heads to provide a through passage 70 for exhaust gases, said conduit having a portion of its length provided with a plurality of relatively small apertures, an intermediate shell having both ends thereof spaced from said heads, a partition between said conduit and said intermediate shell and dividing the space between 75

said conduit and intermediate shell into a plurality of inner elongated chambers, a partition dividing the space between said intermediate and outer shell into a plurality of outer resonator chambers, the inner chamber at each end of the muffler communicating around the adjacent end of the intermediate shell with a resonating chamber, said conduit being provided with apertures opening into each inner chamber and being provided with imperforate portions near the ends of said conduit forming with the intermediate shell resonator necks connecting with said resonator cavities, and a tail pipe which has fundamental resonance frequencies in harmonic relation to those of the resonator chambers within said muffler.

4. A muffler including a tail pipe, and a sound and gas conducting conduit extending through said muffler and having a portion thereof provided with perforations, resonator chambers each coupled acoustically with said conduit through said perforations by means of a neck portion of less cross sectional area than the cross sectional area of the resonator chamber and having fundamental resonance frequencies corresponding to the natural fundamental frequencies or harmonics of said tail pipe.

5. A muffler for use in connection with silencing the exhaust from an internal combustion engine and having a tail pipe, a main conduit through which the gases pass, an intermediate shell partly surrounding said main conduit and open at an end, and an outer conduit arranged about the intermediate conduit and forming with the same a resonator chamber, said conduit being provided at intervals with perforations through which gases and sound waves may pass from said conduit into the space between said conduit and said intermediate shell, an end part of said intermediate shell forming with an unperforated portion of said conduit a resonator neck, the parts of the muffler being proportioned in accordance with the following formula:

$$45 \quad N = \phi \frac{c}{2\pi R_1} \sqrt{\frac{s}{L_1 v}}$$

in which N =frequency to be attenuated

ϕ =area of perforation in conduit communicating with the neck divided by the cross sectional area of the conduit, the former area not exceeding the latter area;

c =velocity of sound in the medium;

s =cross-sectional area of resonator neck, which should be approximately equal to the cross sectional area of the conduit;

L =length of resonator neck

v =volume of cavity.

6. A muffler for use in connection with silencing the exhaust from an internal combustion engine and having a tail pipe, a main conduit through which the gases pass, an intermediate shell partly surrounding said main conduit and open at an end, and an outer conduit arranged about the intermediate conduit and forming with the same a resonator chamber, said conduit being provided at intervals with perforations through which gases and sound waves may pass from said conduit into the space between said conduit and said intermediate shell, an end part of said intermediate shell forming with an unperforated portion of said conduit a resonator neck, the parts of the muffler being proportioned in accordance with the following formula:—

$$N = \phi \frac{cR}{2\pi R_1} \sqrt{\frac{I}{LL_1}}$$

in which: N =frequency to be attenuated

ϕ =area of perforation in conduit communicating with the neck, divided by the cross sectional area of the conduit, the former area not exceeding the latter area;

c =velocity of sound in the medium

R =radius of a circle of equal cross-sectional area as the neck which cross sectional area should be approximately equal to the cross sectional area of the conduit

L =length of neck

L_1 =length of cavity

R_1 =radius of a circle of equal cross-sectional area as the cavity.

7. A muffler having a sound and gas conduit extending therethrough, intermediate and outer shells arranged about said conduit, end heads connected with said outer shell and having apertures in alignment with said conduit and spaced beyond the ends of said intermediate shell, said conduit having a perforated portion of less length than said intermediate shell and terminating at distances from the ends of said intermediate shell, and an annular supporting member secured to an end of said intermediate shell and extending outwardly from said intermediate shell and having its outer part secured to another part of said muffler for supporting said end of said intermediate shell and having apertures through which gases and sound waves may pass from the space between said conduit and intermediate shell to the space between said intermediate and outer shells, the combined area of the apertures in said supporting member being approximately equal to the cross sectional area of the space between said conduit and the intermediate shell.

LAURENCE R. HEATH. 60
